UNITED STATES PATENT OFFICE.

LOUIS S. SCHER, OF NEW YORK, N. Y.

TELEPHONE-MUFFLER.

1,399,083.

Specification of Letters Patent.

Patented Dec. 6, 1921.

Application filed April 21, 1921. Serial No. 463,190.

To all whom it may concern:

Be it known that I, LOUIS S. SCHER, a citizen of the United States, and resident of New York city, in the county of Bronx and 5 State of New York, have invented certain new and useful Improvements in Telephone-Mufflers, of which the following is a specification.

The invention relates to a telephone muffler, that is an attachment for telephone mouthpieces comprising a member having an opening with which the opening of the mouthpiece communicates and another opening into which the user of the telephone 10 speaks. The device is adapted to enable the user of the telephone to hold private conversation at his desk without being overheard in the same room, and it also is adapted to prevent foreign noises or sounds, 15 such as the rattle of a typewriter or the like, from being transmitted by the telephone. It may, therefore, be said in a general way that the invention performs the functions of a telephone booth, while at the same time 20 it comprises merely a simple attachment for an ordinary telephone transmitter which may very readily be placed in position and removed therefrom.

The effects referred to are obtained by the 25 provision of a mouth opening into which the voice of the user may be directed in such a manner as to exclude foreign sounds to a considerable extent, the device having an interior space which comprises a passageway 30 between the mouth opening and the mouthpiece opening. The device is also constructed in such a manner as to prevent to a considerable extent reflection of sounds from the inner surfaces of the chamber or member 35 into which the person using the telephone speaks, so that the articulation of the voice as transmitted by the telephone will be considerably improved. This effect is obtained by providing walls or surfaces within the 40 interior of the device which are so constructed as to absorb sound waves which move in a lateral direction from the passageway connecting the mouth opening and the mouthpiece opening of the device. Preferably, 45 the device is provided with interior spaces extending laterally on both sides of the passage connecting the two openings referred to, these extended spaces being terminated by wall constructions of material 50 which will absorb, or will not reflect to any extent, the sound waves which move later-

ally within the device. Therefore, there will be no interference between the sound waves which travel from the mouth opening to the mouthpiece opening by sound waves 60 which might be reflected from the walls of the passageway connecting the two openings. It will also be noted that the mouth opening is comparatively near to the mouthpiece opening, so that the lips of the speaker may 65 be brought within the required distance of the mouthpiece.

An object of the invention is the provision of a simple and effective device of the character referred to.

Other objects of the invention consist in various combinations of parts and improved constructions, all of which will be more fully described hereinafter and particularly set forth in the appended claims.

In order that a clearer understanding of the invention may be had, attention is hereby directed to the accompanying drawings forming part of this application and illustrating one embodiment of the invention.

In the drawings—

Figure 1 represents a front elevation of a device embodying my invention applied to a telephone transmitter;

Fig. 2 is a horizontal section taken on line 2—2 of Fig. 1;

Fig. 3 is a vertical cross-section taken on line 3—3 of Fig. 2; and

Fig. 4 is an end elevation of one of the separate members containing sound-absorb- 90 ent material which may be positioned in one of the lateral extensions of the device.

Referring to the drawings, the device may comprise a shell 1 made of suitable material such as pressed metal. This shell is provided 95 with an opening 2 at one side into which the user of the telephone may speak and with an opening 3 by which connection may be made with the mouthpiece of a telephone transmitter, indicated in dotted lines at 4. 100 The openings 2 and 3 are preferably in alignment with each other on opposite sides of the device, midway of the length thereof.

The shell of the device may be formed in any suitable way as by forming the same in 105 several sections which may be secured together to form a hollow structure which is open at the two ends. The front wall 5 of the device is preferably curved outwardly, as is shown at 6, the mouth opening 2 being 110 formed in this outwardly curved portion of the shell. The mouth opening is preferably

provided with a circular rim 7 within which the lips of the speaker may be inserted, the opening being of such a size that the lips will fit closely therein, so as to prevent to 5 a considerable extent the entrance of foreign sounds into the opening. It will likewise be noted that with this construction the sound waves produced by the speaker's voice will all enter the interior of the device, so 10 that the voice of the speaker will be practically inaudible to a person close by. This effect is, of course, greatly increased by the interior construction of the device, whereby sound waves directed laterally within the 15 device are absorbed to a large extent, and there is practically no vibration of the walls of the device, which might produce sound.

The opening 3 for the mouthpiece is preferably formed by bending the metal of the 20 rear surface 8 of the device inwardly in the form of a short tube 9, the metal comprising tube 9 being provided with a narrow inwardly directed annular flange 10. An annular member 11 of felt or similar material 25 is preferably positioned upon flange 10.

The telephone mouthpiece is inserted within opening 3, so that its outer edge will engage against the cushion 11, this preventing the escape of sound through opening 3 to a 30 greater extent than otherwise would be the case. When the device has been positioned by inserting the mouthpiece into opening 3, it may be held in position by means of screws 12, which extend through openings in the 35 upper and lower walls of the device into engagement with the telephone mouthpiece.

The interior space of the device is preferably provided, as stated, with lateral extensions, whereby an elongated chamber is 40 formed at each side of the passageway connecting the mouth and mouthpiece openings. These elongated chambers are provided, as stated, with walls or surfaces of sound-absorbent material. Preferably, the sound-absorbent material is positioned at the ends 45 of these chambers, the side walls of the chambers preferably being flared outwardly from their central portion toward the ends of the same, as is indicated at 13. With this 50 construction any sound waves which impinge against the side walls of the laterally extending chambers will be reflected thereby toward the sound absorbent material at the ends of the said chambers. All sound 55 waves which do not proceed directly from the mouth opening to the mouthpiece opening and which are not necessary for the telephone transmission, are directed and reflected by the flared walls toward the said 60 sound absorbent material, where they are wholly absorbed and prevented from further reverberating within the chamber.

The sound-absorbent material, or material which provides poor reflecting surfaces 65 for sound waves, preferably takes the form

of loosely arranged fibrous material such as felt or the like.

In the preferred construction separate open-ended members 14 are provided, which may be inserted into the device from the 70 ends thereof, members 14 being so curved as to fit closely within the curved walls 13 of the device. Members 14 have the loose fibrous material referred to packed or positioned therein. Preferably this takes the 75 form of a layer 15 of comparatively soft felt and a layer 16 outside the same of comparatively hard felt. The members 14 themselves may be formed of any suitable material, such for example as cardboard or 80 the like. The layers 15 and 16 provide a sufficient thickness of sound absorbent material to largely or wholly absorb the sound waves directed against them, a considerable thickness being required, according to my 85 experience, to accomplish the purpose in such a device.

In the preferred construction the ends of the device are closed by cap or cover members 17, which may be removably positioned 90 on the ends of the device. Preferably these cap members 17 are provided with side flanges 18, so that they may be positioned by simply sliding the same over the end portions of the device into position to close the 95 ends of the device.

It will be noted that the provision of the separate members 14 containing the fibrous material tends to make the device more sanitary than it otherwise would be since these 100 members 14 may be taken out and replaced by similar members containing fresh fibrous material, whenever desired. The fibrous material may, of course, be sprayed or impregnated whenever necessary with antiseptic fluid. 105

It will be observed that the lips of the speaker, when applied to opening 2, are within about one-half inch of the mouthpiece 4, in my preferred construction, which 110 is considered by telephone engineers to be the proper distance. It will also be observed that the outwardly curved bulge 3 of the casing, in which the mouth opening is situated, aids in producing clear articulation when the device is used. Because of this curvature, and the sharp edge to the mouth opening which is provided, the sound waves or portions thereof which tend to travel laterally from the edges of the mouth 115 opening are permitted to do so unimpeded, and consequently the articulation is clearer than it would be if these waves were obstructed or confined.

It will also be noted that the plate indicated at 19, bearing the subscriber's number, is not hidden or obscured by the use of the device described, the curvature of the outside of the device, corresponding to the flare 125 of the inside walls of the lateral extensions, 130

serving the additional function of leaving the view of the number plate unobstructed.

It will be noted that the invention is not limited strictly to the details of construction which have been particularly described, but that the same is as broad as is indicated by the accompanying claims.

What I claim is:

1. A device of the character described, 10 comprising a member having a telephone mouthpiece opening, an opening to which the mouth of the user may be applied, and laterally extending wings the side walls of which taper outwardly toward their 15 outer ends, said member having an interior space providing a passageway between said openings and extending into said wings.

2. A device of the character described, 20 comprising a member having a telephone mouthpiece opening, an opening to which the mouth of the user may be applied, and an interior space providing a passage between said openings with lateral extensions, the front wall of said member having a forwardly and laterally extending protuberance 25 in which said mouth opening is situated.

3. A device of the character described, 30 comprising a member having a telephone mouthpiece opening at the rear, an opening to which the mouth of the user may be applied at the front, and an interior space providing a passage between said openings, said space having laterally extending chambers filled, for a considerable distance laterally, with sound absorbent material, at each 35 side of said passage.

4. A device of the character described, 40 comprising a member having a telephone mouthpiece opening, an opening to which the mouth of the user may be applied, and an interior space providing a passage between said openings, said space having laterally extending chambers, at each side of said passage, having sound absorbent material at the ends thereof, and side walls so shaped as to direct against said material all sound waves which do not enter said mouthpiece opening.

5. A device of the character described, 50 comprising a member having a telephone mouthpiece opening, an opening to which the mouth of the user may be applied, and an interior space providing a passage between said openings, with lateral extensions having side walls which curve outwardly toward their outer ends, said extensions having sound absorbent material extending across their outer ends.

6. A device of the character described, 60 comprising a member having an opening for a telephone mouthpiece, and a mouth opening, said member having a wall structure for absorbing sound waves, comprising

a layer of loose fibrous material on the inside, and a layer of harder, more compact, 65 fibrous material on the outer side of said first layer.

7. A device of the character described, 70 comprising a member having an opening for a telephone mouthpiece, and an opening to which the mouth of the user may be applied, and an interior space providing a passage between said openings, with lateral extensions, the latter having side walls which flare outwardly toward their outer 75 ends.

8. A device of the character described, 80 comprising a member having an opening for the telephone mouthpiece, an opening to which the mouth of the user may be applied, and an interior space providing a passage between said openings, with lateral extensions, and separate members inserted in said extensions, containing loose fibrous material.

9. A device of the character described, 85 comprising a member having an opening for the telephone mouthpiece, an opening to which the mouth of the user may be applied, and an interior space providing a passage between said openings, with outwardly flaring lateral extensions arranged to provide unobstructed chambers for a distance at each side of said passage, and provided with sound absorbent material for a considerable distance beyond said chambers. 90

10. A device of the character described, 100 comprising a member having an opening for the telephone mouthpiece, an opening to which the mouth of the user may be applied, and an interior space providing a passageway between said openings, with lateral extensions, and an end wall structure for each said extension, comprising a layer of loose fibrous material on the inside, 105 and a layer of harder, more compact, fibrous material on the outer side of said first layer.

11. A device of the character described, 110 comprising a member adapted to be mounted on a telephone mouthpiece, said member having a front opening to which the mouth of the user may be applied, and a rear opening in alinement therewith for the mouthpiece, formed by bending the material of the rear side of the member forwardly to form a short forwardly extending tube within the member, having a front annular flange against which the mouthpiece may abut, said member having an interior space 115 providing a passage between said openings. 120

Signed at New York, in the county of New York, and State of New York, this 19th day of April, A. D. 1921.

LOUIS S. SCHER.
